ADJUSTABLE POWDER DISPENSER

Filed Nov. 21, 1925

Inventor
Alfred J. Krank

By *Horand Pfeifer*

Attorney

UNITED STATES PATENT OFFICE.

ALFRED J. KRANK, OF ST. PAUL, MINNESOTA.

ADJUSTABLE POWDER DISPENSER.

Application filed November 21, 1925. Serial No. 70,502.

My invention relates to an improvement in an adjustable powder dispenser wherein it is desired to provide means of dispensing powder, such as face or toilet powder in a 5 suitable compact.

A feature of the invention resides in means for providing a compartment wherein the powder is held and associated therewith a dispensing member which is adapted 10 to cut into the powder and dispense the powder in a measured amount through openings into the powder puff compartment. This provides means so that only the desired amount of powder is dispensed to the 15 puff and puff compartment and thereby prevents waste of the powder or spilling of the same when the powder compact is open.

My invention further includes means providing air engaging member which permits 20 the easy engagement of the dispensing member of my powder dispenser so that the same can be rotated to dispense from the powder storage compartment the desired amount of powder into the powder puff compartment. 25 This engaging member forms a lever means or finger engagement so that the operator can easily turn and rotate the dispensing member of my device.

Further, the invention includes a means 30 for holding a powder puff within the compartment, the holding means providing the lever member for operating the dispensing member and being secured in a manner, in one form of my invention, so that it can 35 be elevated to permit the powder puff to be readily removed from the powder compartment. This member is adapted to hold the puff in the powder compartment ordinarily.

These features, together with other objects and particular construction of my invention will be more fully set forth in the specification and claims.

In the drawings forming part of my specification:

45 Figure 1 illustrates a side view of my adjustable powder dispenser or compact.

Figure 2 is a section on the line 2—2 of Figure 1.

50 Figure 3 is a plan view of the powder dispensing member removed from the dispenser or compact.

Figure 4 is a section on the line 4—4 of Figure 3.

Figure 5 is a plan view similar to Figure 3 with the powder puff removed from the 55 dispenser.

Figure 6 is a section on the line 6—6 of Figure 5.

Figure 7 is a plan view of another form 60 of my invention of the dispenser.

Figure 8 is a bottom view of my adjustable powder compact and dispenser.

In the drawings my powder compact or dispenser A is provided with a cover B and a bottom portion C. The portions B and C 65 are hinged together at 10 so as to provide a compact or powder dispenser which is ordinarily made quite thin and which is illustrated in enlarged formation in the drawings.

70 My adjustable powder dispenser A is provided with a dispensing member 11 which fits into the bottom C, as illustrated in Figure 2 and is provided with a series of cutting points 12 which project into the powder compartment 13 formed by the lower portion C of the compact A. The formation of the cutting points is such as to form 75 openings 14 so that when the cutting points 12 engage the powder in the compartment 13, by rotating the dispenser 11 the powder will ooze up through the openings 14 into the puff compartment 15 formed in the top 80 of the dispenser 11.

85 The powder puff 16 is adapted to be held within the compartment 15 by means of the lever or bar member 17 which is hinged on one end at 18 and the free end 19 of which is snapped into engagement with the in-turned edge 20 through the opening 21 90 formed in the dispenser 11. This construction permits the lever and closure member 17 to be lifted so that the puff 16 may be easily lifted out of the puff compartment 15 by raising the free end 19 of the lever 95 member 17, as illustrated in dotted outline in Figure 5.

100 The lever or bar member 17 projects across the open top of the dispenser 11 and is adapted to form a lever engaging means so as to permit the easy rotation of the dispensing member 11 by the operator. The lever member 17 is cut away at 22 and 23 with an enlarged central portion 24. In this manner the recesses 22 and 23 form 105 finger engaging recesses in which the fin-

gers fit readily and which permit the dispenser 11 to be easily turned and operated. As the dispenser is rotated, the powder will be cut by the points 12 so that the loose powder will be forced up through or ooze out of the openings 14 into the puff compartment 15.

When the powder compartment 13 is practically empty the lever operating member 17 forms a convenient handle for permitting the dispensing member 11 to be raised out of the powder compartment 13, and as the powder is used up from the compartment 13 the dispensing member 11 gradually descends into the compartment 13.

In Figure 7 I have illustrated the dispensing member 11 provided with a bar or lever member 17 which has its ends 25 fixed to the inturned edge 20 of the dispenser 11. In this construction the lever 17 forms a suitable cross-bar which may be engaged by the fingers so as to permit the free rotation of the dispensing member 11 and also forms a holding means which extends across the puff 16 to hold the same against falling out of the dispensing member by permitting it to be engaged by the tongue 16', so that it may be readily removed from over the member 17.

In the bottom C of my dispenser A I provide a formation of a design such as 26 which projects into the compartment 13 sufficiently to form a shoulder means for engaging the loose powder 13 to hold the same from caking into a pack and rotating as a whole when the gripping and cutting fingers engage the powder.

My powder dispenser is adjustable to dispense just the desired amount of powder into the powder puff compartment and thus the operator can use powder from the compartment 13 without wasting it or without danger of having too much powder on the puff at one time. The advantage of this construction provides a dispenser so that when the puff is removed, the powder which is in the compartment 13 and is in a loose powdered state, will not fall out, even though the compact A is tipped to one side, as the dispensing member 11 fits snugly and frictionally into the sides of the compartment 13.

The lever operating member 17 provides means for permitting the easy rotation by providing a finger leverage so that the dispensing member 11 can be easily rotated. Without this member it would be difficult to rotate the dispensing member 11 owing to the frictional contact of the same within the compartment 13. Further, the lever 17 forms a handle means for lifting the dispensing member 11 out of the compartment 13 when it is desired or for holding the puff within the powder compartment of the dispensing member.

In accordance with the patent statutes I have described the principles of operation of my adjustable powder dispenser together with the best embodiment thereof, and while I have illustrated a particular formation of the same, I desire to have it understood that the invention can be applied to uses other than those above set forth and carried out by other means within the scope of the following claims.

I claim:

1. An adjustable powder dispenser including, a compact formed with upper and lower portions, one portion of which forms a powder compartment, a rotatable dispensing member adapted to fit frictionally within said powder compartment including cutting points and openings associated therewith to dispense powder therethrough, and lever operating means extending across said dispensing member.

2. A powder compact including a dispensing member, a puff compartment formed in said dispensing member, and handle lever means on said dispensing member adapted to provide finger gripping means to permit the rotation of said dispensing member or the lifting of the same out of said compact.

3. A powder dispenser including, a compartment for loose powder, a dispensing member adapted to be operated in said powder compartment having means for cutting the powder and forcing it into said dispensing member, and lever handle means extending across said dispensing member adapted to form a lifting handle, and a closure for holding a puff in said dispenser.

4. An adjustable powder dispensing compact including, upper and lower members hingedly secured together, one of said members forming a loose powder compartment and the other member forming a cover for closing said compact, a dispensing closure member adapted to be rotatably positioned within the member forming the powder compartment, and bar means having one end hingedly secured, with the other end snapped into a recess adapted to form a handle and lever operating means to permit the rotation of said dispensing member within said compact for the purposes specified.

5. A powder dispenser including, a compact casing, one portion of said casing forming a powder receiving compartment, a powder dispensing member rotatably positioned within said powder receiving compartment and adapted to form a cover to hold the powder from falling out of said powder compartment, an inturned flange formed on said dispenser forming an open top thereto to receive a powder puff through said opening, and a handle lever operating member extending across said open top for the purposes specified.

6. A dispensing member for powder compacts including, a member adapted to provide a closure for a powder compartment, one side of said closure having a series of perforations formed therein in a manner to provide cutting points projecting therefrom, an annular flange formed about the other

side of said dispenser to assist in holding a powder puff in the same, and an operating member extending from one side to the other of said flange member to form finger lever engaging and handle means. 10

ALFRED J. KRANK.
